(57) **CLAIM**

I claim the ornamental design of the dispenser jar, as shown and described.

DESCRIPTION

FIG. 1—is a perspective view of the dispenser jar;

FIG. 2—is a front view thereof;

FIG. 3—is a rear view thereof;

FIG. 4—is a first side view thereof;

FIG. 5—is a second side view thereof;

FIG. 6—is a top view thereof;

FIG. 7 is a bottom view thereof; and,

FIG. 8 is another perspective view showing the dispenser jar. The broken lines around the neck of the dispenser jar show a transparent lid and form no part of the claimed design. Any other broken lines in the drawings represent environmental structure and form no part of the claimed design.
